UNITED STATES PATENT OFFICE

2,101,667

EXHAUST DEVICE

Henry J. Berman, River Forest, Ill., assignor to
Edison General Electric Appliance Company,
Chicago, Ill., a corporation of New York

Application May 16, 1935, Serial No. 21,839

6 Claims. (Cl. 15—15)

This invention relates to exhaust devices, more particularly to exhaust tables for brushing vitreous enameled products, such as parts of an electric range, and it has for its object the provision of an improved device of this character.

In accordance with this invention, an exhaust chamber is provided. Arranged above this chamber are a plurality of spaced apart members having surfaces inclined downwardly toward the exhaust chamber so as to direct loose enamel, etc. to the exhaust chamber through the spaces between the members. Supported above the spaced members is a work receiving tray arranged for movement longitudinally of the members and also for rotary motion with reference to them. A hood is provided around the tray arranged to direct the inflowing air over the parts being brushed.

For a more complete understanding of this invention, reference should be had to the accompanying drawing in which Fig. 1 is a perspective view illustrating an exhaust device arranged in accordance with this invention; Fig. 2 is a front elevation of the exhaust device of Fig. 1; Fig. 3 is a side elevation of the exhaust device of Fig. 1; Fig. 4 is a fragmentary perspective view illustrating a portion of the exhaust device of Figs. 1, 2 and 3; Fig. 5 is an elevation, partly in section, of a portion of the device shown in Figs. 1, 2 and 3; and Fig. 6 is a sectional view taken through the line 6—6 of Fig. 5 and looking in the direction of the arrows.

Referring to the drawing, this invention has been shown in one form as applied to an exhaust device comprising an exhaust table 10. This table comprises a substantially rectangular support 11, which, as shown, is provided with a pair of front and rear walls and a pair of side walls joined together in any suitable manner.

The support 11 in turn is supported by means of a plurality of legs 12 arranged at the corners.

Arranged longitudinally of the support 11 from the front to the rear wall thereof are a plurality of spaced metallic members 13 having substantially the shape of an inverted V. As shown, there are three of these members arranged between the side walls of the support. Adjacent the side walls of the support are a pair of metallic members 14 inclined downwardly from the upper edges of the side walls and inwardly toward the members 13, as shown in the drawing. These members 14 are also spaced from the adjacent members 13. The spaces between the members 13 and 14 are designated by the numeral 14a.

Arranged below the members 13 and 14 is an

exhaust chamber 15 which is connected with a suitable exhaust conduit 16. It will be understood that the conduit 16 will be connected with a suitable exhaust device (not shown) arranged to create a low pressure in the exhaust chamber. 5

While the members 13 and 14 are shown in the drawing arranged longitudinally of the support 11, it will be understood that they may be positioned transversely of the support. When the members are positioned longitudinally of the support, it is preferable that the spaces 14a between the members be somewhat wider at the front of the device than at the rear. For example, the members 13 and 14 may be so arranged that they touch each other at the rear, as shown in Fig. 1, 15 while the space between the members varies gradually from zero at the rear to the widest portion which is located at the front. This arrangement has the advantage that more air is exhausted from the work table at the front 20 where the operator works than at the rear, which, of course, is very desirable.

Supported by the front and rear walls of the support 11 are a pair of rails 17 which in turn support a work carriage 18. The work carriage, 25 as shown in the drawing, is of openwork construction, being formed by a rectangular frame 19 to which wheels 20 are attached. The wheels 20, as shown, ride upon the rails 17. The carriage 18, as shown, is arranged to move longitudinally 30 from the front to the rear of the support 11 on the rails 17. The carriage 18 supports an openwork supporting tray 21 for the work articles that are brushed. The tray 21, as shown, is also 35 of openwork construction, and is made of a rectangular wire 22 which is somewhat larger than the rectangular support 18. The corners of the wire 22, as shown, are joined to a hub portion 23 by means of wire spokes 24. The hub 23 is mounted upon a stud 25 (Figs. 5 and 6) which 40 is supported by means of a supporting collar 26. The collar 26 is supported by means of arms 27 secured to the collar and extending radially therefrom to the corners of the frame 18 where they are secured. The stud 25 is provided with 45 four vertical slots 25a arranged 90° apart. A spherical member 26a is carried by the collar 26 arranged to be received in the slots 25a selectively. The sphere 26a is pressed into the slots 25a by means of a compression spring 26b. The 50 sphere and slots function as means to hold the latch in each of four positions spaced 90° apart.

It will be observed in view of the foregoing construction, that the work which is positioned upon the tray 22 can be rotated relative to the 55

carriage 18, and furthermore, can be moved longitudinally relative to the frame 11 on the carriage 18. This construction has the advantage that the work to be brushed may be turned on a vertical axis and may also be pushed forward and backward for the convenience of the operator, and also in order to keep the parts being brushed always over the most powerful exhausting area, which as has been pointed out previously, is at 10 the front.

In order to exhaust the loose enamel parts, etc. of the work being brushed with a minimum quantity of air, it is necessary to direct the air flowing in over the work table about the area 15 being brushed at a relatively high velocity. In order to assist in this, a suitable hood 28 is provided about the work table.

The hood, as shown, surrounds the support 11, and at the front is provided with a wall 29 20 which has substantially the same height as the front wall of the support 11 and which is spaced somewhat therefrom, as clearly shown in the drawing. The hood is also provided with a side wall 30 which is spaced from the corresponding 25 adjacent side wall of the support 11, but which is considerably higher than this side wall, as more clearly shown in Figs. 2 and 3. The walls 29 and 30 flare outwardly from the corresponding walls of the support, as shown. The front 30 wall 29 and the side wall 30 are connected with the exhaust chamber 15 at points below the lower edges of the corresponding front and side walls of the support 11 so as to provide exhaust ports 31 and 32 below these walls of the support. The 35 front wall 29 where it joins the side wall 30 is provided with an outwardly flared portion 33.

In addition to the front wall 29 and side wall 30, the hood is provided with a side wall 34 opposite the side wall 30. The wall 34 is positioned 40 against the adjacent side wall of the support 11, rather than being spaced from it. The hood also has a similarly arranged rear wall 35 positioned against the rear wall of the support 11. The walls 34 and 35 extend upwardly to the same height as 45 the wall 30, and both side walls 30 and 34 and the rear wall 35 are provided with an inturned substantially horizontal flange 36.

In other words, the hood is closed at the three sides but is open at the front for the convenience 50 of the operator. The inturned flange 36 at the top is so arranged that air that is drawn in at the top is directed in a downward direction over the part that is being brushed away from the operator into the exhaust chamber 15. The opening provided in the top of the hood should be 55 only large enough for the convenience of the operator in handling the work. The side walls 30 and 34 and the end wall 35 flaring outwardly from the support 11 provide space for relatively large 60 parts to be brushed, the particular work area being brushed always being placed at the forward part of the hood by the operator by properly manipulating the carriage 18 and the tray 21. The walls 29 and 30 of the hood are spaced from 65 the corresponding walls of the frame 11 to provide room for free movement of the operator's hand in brushing the edges of the work piece. If the operator be left-handed, the left hand wall of the hood should be spaced from the frame. The 70 flared portion 33 serves to catch loose enamel which is wiped from the work when the operator draws the hand toward the front.

It is to be noted that the angular members 13 and 14 are so arranged that the loose enamel 75 slides down their inclined surfaces into and

through the spaces 14a into the exhaust chamber 15 away from the operator. This is accomplished by a relatively small quantity of air which flows through the spaces 14a with a relatively high velocity.

It is also to be noted that the work tray 21 is so arranged that it can be conveniently manipulated by the operator in order to bring the part that is to be brushed directly before him at the front of the device.

Economy in air consumption is increased by the arrangement of the hood which provides for the flow of air directly downward away from the operator through the work table 10, the opening at the top of the hood being just large enough to 15 provide enough room for the operator to conveniently handle the work.

While I have shown a particular embodiment of my invention, it will be understood, of course, that I do not wish to be limited thereto since 20 many modifications may be made, and I, therefore, contemplate by the appended claims to cover any such modifications as fall within the true spirit and scope of my invention.

What I claim as new and desire to secure by 25 Letters Patent in the United States is:

1. An exhaust device comprising a plurality of elongated members extending between the front and rear of said device and spaced at intervals crosswise thereof, an exhaust chamber below said members, and the spaces between said members gradually increasing from the rear to the front of said device so that more air is exhausted from the device at the front than at the rear.

2. An exhaust device comprising a plurality of 35 elongated members extending between said front and rear of said device and spaced at intervals crosswise thereof, an exhaust chamber below said members, said members having downwardly inclined walls to direct matter falling on them 40 into said exhaust chamber, and the spaces between said members gradually increasing from the rear to the front of said device so that more air is exhausted from the device at the front than at the rear.

3. An exhaust device comprising an exhaust chamber, an openwork tray above said chamber, an openwork carriage supporting said tray, a track above said chamber supporting said carriage for longitudinal movement from the front 50 to the rear of the chamber to carry the tray from the front to the rear, and means mounting said tray on said carriage for rotary motion on an axis substantially perpendicular to the plane of longitudinal movement of the tray.

4. An exhaust device comprising means forming a plurality of air passageways, rails mounted above the plane of said passageways and extending from the front toward the rear of said device, an openwork carriage mounted on said 60 rails for longitudinal movement from the front to the rear thereof, an open-work tray mounted on said carriage, means supporting said tray for rotary motion on said carriage and means for releasably holding said tray in each of a plurality 65 of angular positions relative to said carriage.

5. An exhaust device comprising an open-work support, a reduced pressure chamber below said support and a hood surrounding said support provided with upright walls only at the sides and rear of said support and flanges on the upper edges of said walls extending inwardly toward said support.

6. An exhaust device comprising a substantially rectangular support defined by opposite pairs of 75

substantially upright side and end walls, a plurality of spaced members supported by said walls, a work supporting carriage mounted above said members, walls defining an exhaust chamber below said members adapted to be connected to an exhaust device, and walls defining a hood surrounding said rectangular support, the walls of said hood at the front and at one side being spaced from the adjacent front and side walls of 5 said support and flaring outwardly therefrom, and further, connected to said exhaust chamber walls below the lower edges of said front and side walls of said support to provide air ducts below said walls, the hood wall at the front being

substantially the same height as said front wall of said support and said side wall of said hood being materially higher than the adjacent side wall of said support, the remaining side and end walls of said hood being positioned against the 5 corresponding side and end walls of said support and having portions extending above them to the height of said one side wall of said hood and flaring outwardly, the upper edges of said hood walls at the sides and rear having relatively 10 large flanges turned inwardly toward said carriage.

HENRY J. BERMAN.
